DUAL ADVANCED WARNING AND
CUTOFF SWITCH

Saul Roman, Brooklyn, N.Y., assignor, by mesne assignments, to the United States of America as represented by the Secretary of the Navy

Filed Apr. 7, 1960, Ser. No. 20,785

2 Claims. (Cl. 89—134)

This invention relates to control systems for power operated devices such as guns or missile launchers and more particularly to circuit breaking devices for rendering the firing circuit of such devices inoperative in certain zones of movement.

In the control systems for guns and missile launchers which are fired during traverse, it is common practice to provide some firing cut-out device whereby the firing circuit of the gun or missile launcher is rendered inoperative during such time that the gun or missile launcher is aimed in a direction in which it is undesirable to fire. Such firing cut-out devices are usually found on board ship and on aircraft where the field of fire of a gun or missile launcher includes structure on the ship or aircraft.

It has been the practice in the past to provide a fixed cam which is patterned after the structure of the ship whereby, as the gun or missile launcher is pointing at some portion of the ship's structure, the firing circuit will be rendered inoperative to fire a shell from a gun or a missile from a missile launcher. In the use of devices of this type, the remote operator has been unable to tell when the launcher or gun was approaching one of the unsafe firing zones until the gun or launcher was actually pointing at part of the ship's structure and the firing circuit had been rendered inoperative.

The present invention provides an improved system whereby a warning is given to the remote operator as the gun or launcher approaches one of the unsafe firing zones before the firing circuit has been rendered inoperative. This warning enables the remote operator to ascertain at any given time the attitude of the gun or missile launcher with respect to the ship's structure and take proper steps to control the missile launcher or gun such that the firing circuit will not be rendered inoperative unless it becomes necessary to do so.

One of the objects of this invention is to provide improved firing cut-out control devices for ordnance equipment.

Another object of this invention is to provide an improved firing cut-out device wherein a warning is given as the gun or missile launcher approaches an unsafe firing zone.

A further object is to provide an improved firing cut-out device wherein a warning is given at least 5 degrees of train or elevation before the firing circuit is rendered inoperative.

Other objects and many of the attendant advantages of this invention will be readily appreciated as the same becomes further understood by reference to the following detailed description when considered in connection with the accompanying drawings wherein:

FIG. 1 is a perspective view of the dual advanced warning and cutoff mechanism of this invention and illustrates the relationship of the switch to the cam and lead screw;

FIG. 2 is a front elevational view of the switch with parts broken away;

FIG. 3 is a side elevational view of the switch with parts broken away and depicts a portion of the cam;

FIG. 4 is a plan view of the switch with parts broken away and illustrates a portion of the cam; and

FIG. 5 is a graphic representation of the relationship of the movement of the gun or missile launcher in degrees train and elevation to the switch actuators.

2

Referring to FIG. 1, showing one embodiment of the present invention, a cylindrical cam 10 is supported on shaft 12 and is driven by suitable gears 14 from the training gear 16 of a power operated device such as a gun or missile launcher (not shown) through an intermediate gear box, not shown. The cylindrical cam 10 rotates at any suitable speed ratio with the training movement of the gun or missile launcher, such for example as a ratio of 1 to 8. The rotation of the cylindrical cam corresponds to the rotation of the gun or launcher in azimuth or train.

The cam surface is cut on a cylindrical sheath sleeve 18 which is fastened between clamp plates 20 on a drum 22. The sleeve 18 is cut away over the entire area that represents the safe firing zone and, consequently, the part of the sleeve 18 which is not cut away represents the area into which it is unsafe to fire.

Adjacent to and parallel to the axis of the cylindrical cam 10 is a lead screw 24 which is supported for rotation by brackets 26 and is driven by a suitable gearing 28 from the elevation sector 30 of the gun or launcher. On the lead screw 24, a follower 32 is mounted for movement therewith as the lead screw 24 is rotated by the elevation sector 30. A guide bar 34 is supported in the brackets 26 parallel to the lead screw 24 and extends through the follower 32 to keep the follower from rotating as the lead screw rotates.

A firing cut-out switch 36 and an advance warning switch 38 are mounted on the follower 32 for movement therewith. These two switches are of the plunger type and are mounted in superposed relationship with the advance warning switch 38 uppermost. Mounted on the follower 32 is an advance warning switch actuator 42. Mounted on the follower 32 concentrically with the actuator 42 is a firing cut-out switch 36. The advance warning switch actuator 42, best illustrated in FIG. 3, has an arm 48 which extends outwardly at an angle thereto to engage the plunger 40 of the advance warning switch 38. The end of the advance warning switch actuator 42 opposite the switch plunger 40 engages the cam surface of the cylindrical cam 10. The cam engaging end of the advance warning switch actuator 42 is elliptical in shape, as shown in FIG. 2, for a reason which will be mentioned later. The switch actuator 42 is biased toward the cylindrical cam 10 by suitable springs 50 and the switch actuator 44, which is telescopically mounted within actuator 42, is biased toward the cam 10 by a suitable spring 52. The switch actuator 44 engages the plunger 46 of switch 36 when moved to the left as seen in FIG. 3.

The difference in the speed of the movement of the gun or missile launcher in train and elevation makes it necessary to employ an elliptically shaped cam contacting surface on the advance warning switch actuator 42. The semi-minor axis of the ellipse being equal to 5° of movement of the gun or missile launcher in elevation at a constant training angle and the semi-major axis of the ellipse being equal to 5° of movement of the gun or missile launcher in train at a constant elevation angle.

During operation of the device, and as the gun or missile launcher moves in train, the cylindrical cam 10 is rotated by gearing 14. The cam surface contacts the advance warning switch actuator 42 when the gun or missile launcher approaches a zone into which it is unsafe to fire. The elliptical shape of the cam engaging surface of the advance warning switch actuator 42 causes the advance warning switch 38 to be actuated at a predetermined point such, for example, as 54 mils within the "safe to fire" area. Upon activation, the advance warning switch 38 initiates the flashing of an advance warning light at the radar director (not shown), to thereby warn the remote operator that the gun or missile launcher is approaching an unsafe firing zone.

The cylindrical cam 10 is so formed that the firing cut-

out switch 36 will be actuated slightly short of the "unsafe firing zone," for example at a point 18 mils from the "unsafe firing zone," and the firing circuit is thereby rendered inoperative. As soon as the firing cut-out switch 36 is actuated, the advance warning light ceases to flash and glows steadily until the firing cut-out switch 36 is de-actuated.

De-actuation of the firing cut-out switch 36 will take place after the gun or missile launcher has moved out of the "unsafe firing zone" area such for example at a point 36 mils outside the "unsafe firing zone." At this point, the advance warning light will again commence to flash and will continue to do so until the advance warning switch 38 is de-actuated which will occur when the launcher has moved to another predetermined point such, for example, as a point 54 mils within the "safe to fire" area.

Obviously, many modifications and variations of the present invention are possible in the light of the above teachings. It is therefore to be understood that within the scope of the appended claims the invention may be practiced otherwise than as specifically described.

What is claimed is:

1. A cam-actuated advance warning and cutout switch means comprising a rotatably-mounted cylindrical cam, 25 a follower mounted to reciprocate axially along said cylindrical cam, said follower comprising a pair of switch actuators telescoped with respect to each other, a pair of switches carried by said follower, each actuator being operatively connected to one of said switches, each actuator being resiliently biased into sliding contact with said cylindrical cam, the outer of said telescoping actuators

10
15

being of generally elliptical cross-section, whereby the switch connected to said outer actuator is operated prior to operation of the switch connected to the inner actuator.

2. In a control system for a train and elevation drive system having independently operable train and elevation gearing, a cam-actuated advance warning and cutout switch comprising a rotatably mounted cylindrical cam driven by said train gearing, a lead screw extending parallel to the axis of said cylindrical cam and driven by said elevation gearing, a follower carried by said lead screw, said follower comprising a pair of independently movable switch actuators telescoped with respect to each other and a pair of switches, each actuator being operatively connected to one of said switches and resiliently biased into sliding contact with said cylindrical cam, the outer of said telescoping actuators being of generally elliptical cross-section, whereby said outer actuator closes its associated switch prior to closing of the switch connected to the inner actuator and opens said associated switch after opening of said switch connected to the inner actuator.
